UNITED STATES PATENT OFFICE.

RICHARD J. PRETTIE, OF JAMAICA, NEW YORK, ASSIGNOR TO THE AEOLIAN COMPANY,
A CORPORATION OF CONNECTICUT.

TONE-ARM FOR PHONOGRAHS.

1,294,945.

Specification of Letters Patent.

Patented Feb. 18, 1919.

Application filed July 15, 1915. Serial No. 40,020.

To all whom it may concern:

Be it known that I, RICHARD J. PRETTIE, a citizen of the United States, residing at Jamaica, in the county of Queens and State 5 of New York, have invented certain new and useful Improvements in Tone-Arms for Phonographs, of which the following is a specification.

My present invention relates to an improved tone-arm for phonographs, talking machines, and the like, the structural and operative advantages of which will be readily apparent to those skilled in the art from an understanding of the following description in connection with the drawings.

In the drawings, Figure 1 is a fragmentary vertical section of a talking machine showing my tone-arm in side elevation; Fig. 2 is an enlarged vertical section of the tone-arm shown by itself; Fig. 3 is an enlarged end view looking at the sound-box and tone-arm in Fig. 1 from the left side of said figure, the dotted lines showing the sound-box and the end tone-arm section swiveled into out-of-playing position; Fig. 4 is a section on the line 4—4 in Fig. 2 looking in the direction of the arrows; Fig. 5 is an enlarged section, on the line 5—5 in Fig. 2 looking in the direction of the arrows; and Fig. 6 is an enlarged detail of Fig. 2.

Describing now the specific devices of the drawings, certain of these represent merely the usual talking machine parts. Thus, 1 is the upper portion of the cabinet, 2 the lid, 3 the top shelf, 4 the motor spindle, 5 the turntable, and 6 the neck of the horn.

The tone-arm shown is made up of three sections,—an outer section 7, a middle section 8, and an inner section 9, the sound-box 10 being attached to the outer section.

11 is a stationary vertical sleeve connecting the tone-arm with the horn, and 12 is a horizontal flange by which said sleeve is secured to the small end 6 of the horn. A circular seat or bearing 13 having a convex bottom 36 is provided in the upper end of the sleeve 11. Also a bearing pin 14 is provided concentric with said circular seat, said pin being supported for vertical adjustment by a set screw 15 in the overhanging end of a vertical arm or extension 16 from the sleeve 11, and having a conical end 14^a to coact with a conical hole in the boss 17 in the tone-arm. The convex bottom 36 tends 50 to keep the tone-arm centered on its seat and

the conical end 14^a permits any wear to be taken up by adjusting the pin 14 into a lower position.

The result is that inner section 9 of the tone arm is permitted to swivel about a vertical axis coincident with the pin 14,—as can also the tone-arm sections 7 and 8 and the sound-box, all being supported by or carried with said inner tone-arm section 9.

The middle tone-arm section 8 is straight 65 and is pivoted for vertical play to the section 9 by trunnion-screws 38. One end of said middle section fits into the mouth of the inner section 9 and both are spherically shaped so that the middle section can pivot 70 up and down on said trunnion-screws. These screws have a smooth shank portion adjacent the head received with rotary bearing fit in holes through the tone-arm section 9 (Fig. 5) and have an end shank portion 75 which is reduced and screwed into the wall of the middle tone-arm section reinforced by pieces 18 soldered or brazed thereto. The smooth shank portion is made a trifle longer than the hole through the tone-arm section 9 so to permit section 8 to pivot freely on the section 9.

19 is a stop riveted to the under side of the middle tone-arm section, positioned to bear against the mouth of the inner section, 85 not when the sound-box is in playing position with the needle on the record as in Fig. 1, but only when it has been swung, as will be hereafter explained, into the out-of-playing position shown by the dotted lines in 90 Fig. 3.

The outer tone-arm section 7 is a horizontally disposed elbow, one limb thereof being partly telescoped into the forward end of the middle section 8 and the other limb 95 projecting laterally for connection with the sound-box 10. The wall of the first named limb has a slot 20 in which is located a projection 21 from the middle tone-arm section 8. The result is that the outer section 7 can 100 be rotated about the longitudinal axis of the middle section 8 through an arc equal to the length of the slot 20. Said slot is made of such length and is so positioned that the sound-box 10 can be swung from the vertical 105 position shown by the full lines (Fig. 3) upwardly into the dotted, out-of-playing position wherein it is supported by the end of the aforesaid slot 20 bearing against the projection 21. The projection 21 (Figs. 2 and 110

6) is a smooth end of a screw 22 tapped into a flanged sleeve 23^a projecting outwardly through a hole in the bottom of the middle tone-arm section 8, said sleeve being provided with a washer 23 adjacent the outside of said middle section. A leaf-spring 24 is secured to the middle section also by said screw 22, said spring bearing against the aforesaid washer 23, so that the wall of the 10 middle section is clamped between said washer and the basal flange of the sleeve 23^a whereby the projection 21 is strongly attached to the middle tone-arm section.

The referred to leaf-spring 24 carries a 15 convex projection 25 (Fig. 2) at its free end, which it delivers inwardly through a hole in the middle section. 26 is a cup-like depression in the wall of the outer tone-arm section 7 positioned so that the projection 25 snaps into it when the sections are 20 in the playing position shown by the full lines in Figs. 1 and 3. The result is that the outer and middle tone-arm sections are thereby locked together and act like a single 25 tube,—first, in pivoting vertically about the trunnions 38 when the sound-box rises and falls due to vertical inequalities in rotation of the record and turn-table; and secondly, in swinging horizontally across the face of 30 the record along with the inner tone-arm section 9 as the latter swivels about the pin 14. The weight of the tone-arm is insufficient to overcome this spring catch 25—26, and accordingly the parts remain locked together 35 until the operator desires to lift the sound-box to change the record, whereupon he twists the end tone-arm section 7 and attached sound-box toward the left or dotted position in Fig. 3, the initial twisting 40 causing the projection 25 to ride out of the depression 26, thereby overcoming the spring catch and permitting the parts to be twisted over into the dotted non-playing position. At this time the previously described stop 19 comes into action by preventing the sound-box and outer part of the tone-arm from pivoting downwardly below the position wherein said stop strikes against the mouth of the inner tone-arm 45 section 9.

The sound-box 10 is also of novel construction and being claimed elsewhere need not be described here, other than to say that it has a tubular neck having a pin, the neck 55 telescoping into the mouth of the outer tone-arm section (Fig. 3) with the pin received into a slot or notch in said mouth, said pin and notch both being positioned to give the needle 30 (Fig. 1) the desired or proper 60 inclination to the record.

Finally, referring to Fig. 4, 31 is a pin projecting from the stationary arm 16; and it acts as a stop limiting the swing of the tone-arm in both directions by coacting with

the spaced pins 32 projecting on the same 65 level from the elbow 9.

Having thus described my invention, what I claim is:

1. A tone arm comprising tubular sections one of which is adapted to carry a sound box, the adjacent ends of said sections being relatively rotatable about the axis of the sections as a center, one of said sections having a circumferential recess corresponding in length to the angle of relative rotation of the sections and also having a depression, a sleeve fitted in the other section, a plate having a portion to engage in said depression and thus hold the sound box carrying section in a predetermined position 80 against rotation, and a screw operative to secure said sleeve and plate together and to the respective section and having a portion projecting into said circumferential recess to limit the angle of relative rotation of the 85 sections.

2. A tone arm comprising tubular sections one of which is adapted to carry a sound box, an end of one section fitting telescopically and rotatably within the other section, 90 one of said sections having a circumferential recess and also a depression, a retractile member having a part arranged to engage in said depression and thereby hold the sections at a predetermined angle of rotation, 95 and a screw operative to secure said member to the respective section of the tone arm and having a portion projecting into said circumferential recess to limit the angle of relative rotation of the sections. 100

3. A tone arm comprising tubular sections one of which is adapted to carry a sound box, an end of one section fitting telescopically and rotatably within the other section, one of said sections having a circumferential 105 seat and also a depression, a sleeve fitted into the wall of the other section, a spring plate having a projection arranged to coöperate with said depression to hold said sections at a predetermined point against rotation, and a screw operative to secure said sleeve and spring plate together and to the respective section, said screw having a portion projecting into said circumferential seat to limit the angle of relative rotation and to prevent 110 relative longitudinal movement of the sections. 115

4. A tone-arm comprising two tubular sections, one of said sections being rotatable within the other, means for limiting said 120 rotation comprising a recess on the one part and a pin in said recess on the other part, said pin being the end of a screw tapped into a flanged sleeve which projects outwardly through a hole in the outside tone-arm section, the projecting outer end of the sleeve being surrounded by a washer which is forced by the head of the screw into 125

contact with said tone-arm section so that said section is clamped between said washer and the flanged portion of the sleeve.

5. A tone-arm comprising two tubular sections, one of said sections being rotatable within the other, means for limiting said rotation comprising a recess on the one part and a pin in said recess on the other part, said pin being the end of a screw tapped 10 into a flanged sleeve which projects outwardly through a hole in the outside tone-arm section, the projecting outer end of the sleeve being surrounded by a washer which

is forced by the head of the screw into contact with said tone-arm section so that 15 said section is clamped between said washer and the flanged portion of the sleeve; and a leaf-spring secured under the head of the aforesaid screw, said spring projecting adjacent the other tone-arm section, which latter 20 is there recessed to receive a projection on the spring.

In testimony whereof, I have signed my name to this specification, this 14 day of July, 1915.

RICHARD J. PRETTIE.
